DESCRIPTION

U.S. PATENT DOCUMENTS

FIG. 1 is a perspective view of a combined video printer and
player/recorder showing my new design;

D315,157 S * 3/1991 Sogabe D14/156
D328,896 S * 8/1992 Warburton D14/188
D374,031 S 9/1996 Ikenaga
D405,107 S * 2/1999 Yokokawa D18/50
D427,627 S 7/2000 Ikenaga
D428,051 S 7/2000 Ikenaga
D429,706 S 8/2000 Miyazaki
D430,551 S * 9/2000 Shiono D14/156

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
